UNITED STATES PATENT OFFICE.

JOHN FERGUSON, OF HOBOKEN, NEW JERSEY.

FURNACE-GRAVE.

No. 830,705.

Specification of Letters Patent.

Patented Sept. 11, 1906.

Application filed July 29, 1904. Serial No. 518,735.

To all whom it may concern:

Be it known that I, JOHN FERGUSON, a citizen of the United States, residing at Hoboken, in the county of Hudson and State of New Jersey, have invented a new and useful Improvement in Furnace-Grates, of which the following is a specification.

This invention is an improved construction of grate for steam-boiler furnaces and the like.

The object of the invention is to provide a grate which will provide a maximum support for the fuel and at the same time permit a maximum amount of air to pass there-through.

Another very important object is to provide a grate consisting of a plurality of dumping-sections, said dumping-sections being so arranged that the live coals and unconsumed fuel can be arranged upon one section and the clinkers and cinders upon the other section, which section is then dumped, thereby discharging the clinkers and cinders into the ash-chamber, all of which operations are carried on without materially lowering the temperature in the fire-box, thereby permitting the grate to be cleaned as often as desired without drawing the fire, it being understood that after one section has been dumped the operation can be reversed and the other section dumped, thereby thoroughly cleaning both sections of the grate.

Another object of the invention is to provide each grate-section with a series of grate-bars, which have alternating up and down movements, whereby the fire upon said section is agitated from the top to the bottom and the ashes dropped through the bars and the clinkers worked to the top of the burning mass, so that they can be readily shifted to the other section preparatory to dumping.

Another object of the invention is to provide novel means for operating the grate-bars and also a novel form of dumping mechanism.

With these objects in view and also with certain others hereinafter explained the invention consists, essentially, in arranging two dumping-grate sections within a suitable frame, each section consisting of a series of grate-bars, said bars being alternately movable in opposite directions, said sections and their bars being independent of each other, together with means for dumping the sections and also means for operating the bars.

The invention consists also in various fea-

tures of construction hereinafter fully described, and pointed out in the claims.

In the drawings, forming a part of this specification, Figure 1 is a perspective view of a furnace-grate constructed in accordance with my invention. Fig. 2 is a sectional view taken through the grate and showing all of the parts in their normal positions. Fig. 3 is a similar view showing the grate-bars of the rear grate-section moved or shifted. Fig. 4 is a sectional view showing the manner of dumping the section. Fig. 5 is a detail perspective view of one of the shoes employed for moving the grate-bars. Fig. 6 is a detail in perspective and section illustrating the mechanism for raising and lowering the grate-bars. Fig. 7 is a detail view showing the manner of interlocking the grate-bar with the rocker-bar upon which it is supported. Fig. 8 is a detail perspective view showing one end of the cradle which carries the rocker-bars, and also the detachable toothed bar which is arranged at the end of the grate-section. Fig. 9 is a detail sectional view of said toothed bar. Fig. 10 is a detail section showing a portion of the cradle, rocker-bar, detachable toothed bar, and frame. Fig. 11 is a detail perspective view of one of the rocker-bars. Fig. 12 is a top plan view of one of the said rocker-bars. Figs. 13 and 14 are sections of said bar, taken on the lines 13-13 and 14-14 of Fig. 11. Fig. 15 is a section on the line 15-15 of Fig. 2. Fig. 16 is a section on the line 16-16 of Fig. 2. Fig. 17 is a detail perspective view of one of the side members of the grate. Fig. 18 is a detail perspective view of the front member of the grate. Fig. 19 is a detail perspective view of the rear member of the grate. Fig. 20 is a sectional view of the front member. Fig. 21 is a sectional view of the rear member. Fig. 22 is a detail perspective view of one of the grate-bars. Fig. 23 is a top plan view of the same with parts broken away. Fig. 24 is a side elevation partly in section with parts broken away. Figs. 25 and 26 are sectional views on the lines 25-25 and 26-26 of Fig. 24, certain parts in elevation being omitted.

In the practical embodiment of my invention I employ a suitable framework A, consisting of the side members A', front member A'', and the rear member A'', said members being constructed with overlapping vertically-bored portions A'', through which the fastening-bolts are passed for the purpose of 105 110

securely locking the said members together in the form of a rectangle. The side members A' are constructed with suitable supporting legs A⁵ and are provided with deep-seated bearing portions A⁶ directly in line with said supporting-legs. It will be noted by reference to Figs. 1, 17, and 18 that the ends of the members are cut away, as shown at A¹¹, so that when the portions A⁴ are arranged in alignment the top of the frame will be entirely within one horizontal plane.

The grate-sections B are each composed of a series of grate-bars C, which are specially constructed and form the subject-matter of a separate application filed of even date herewith. These grate-bars C are arranged parallel with the side members of the frame, and inasmuch as there are two sections to the grate, the front and rear sections, it will of course be understood that each grate-bar is only one-half the length of the frame. Each grate-bar consists of a serpentine top portion C', which is cast integral with the longitudinal web C², which web is provided with bearing portions C³ either upon the lower edge of the web C² or at the lower end of the depending leg C⁴. Each grate-bar is provided with two bearing portions C³, and it will be noted that the bars with the depending legs are arranged alternately with those devoid of such legs. Each series of grate-bars is supported upon two rocker-bars D, which extend transversely beneath the entire series of grate-bars, said rocker-bars having an alternating series of journal portions D', which fit into the bearing portions C³, carried by the grate-bars, and it will be noted that the journal portions D' are in different horizontal and vertical planes, so that the alternating grate-bars with and without depending legs can be held in the same horizontal plane when all the parts are in their normal positions, as most clearly shown in Figs. 1, 2, 15, and 16. The journal portions D' are connected by means of a series of obliquely-arranged webs D², and at the end of each journal portion is arranged an inwardly-extending locking-lug D³, which is adapted to engage a curved laterally-projecting lug C⁵, arranged upon the opposite ends of each bearing portion C³, said locking-lugs serving to lock the grate-bar and the rocker-bars together, thereby preventing the displacement of the grate-bars, it being understood that in order to connect the grate-bars and rocker-bars together it is only necessary to arrange the said parts at such an angle that the lugs D³ will clear the curved lugs C⁵ and when the parts are brought back to their normal positions the overlapping lugs D³ will engage the laterally-projecting lugs C⁵. Rocker-bars D are arranged in a cradle E, consisting of the side members E' and the connecting cross-bars E², said side members of the cradle being provided with outwardly-projecting trunnions E³, which are journaled

in the bearings A⁶, produced in the side members of the frame. The ends of the rocker-bars are provided with knife-edge bearing-lugs D⁴, which fit into and rest within the V-shaped openings E⁴, produced in the side members E' of the cradle E, the openings E⁴ being sufficiently wide to permit a rocking motion of the lugs D⁴ therein, and it will be noted by reference to Figs. 13 and 14 that the lower end of the lug D⁴, which forms the pivot 75 of the rocking bar D, is slightly above a line drawn through the centers of the journal portions D', so that when the said rocking bars are rocked or vibrated the journal portions will be raised and lowered, thereby causing 80 the grate-bars to be alternately raised and lowered, and by rocking the bars D and causing the grate-bars to move up and down the fuel arranged thereon can be agitated, so as to sift the ashes through the grate and work 85 the cinders and non-combustible portions of the fuel up to the top surface, so that it can be raked from one section of the grate to the other, if desired.

In order to rock the bars D for the purpose 90 of moving the grate-bars up and down, I provide the rear rocker-bar of each section with an integral depending arm D⁵, the lower horizontal member D⁶ thereof being adapted to be engaged by a shoe F, arranged upon a shaker-bar F', sliding in brackets F², depending from the front and rear members of the frame, the forward end of said shaker-bar being connected to the lever F³, pivoted at the front of the frame, a detachable handle F⁴ 100 being adapted to be connected to the upper end of the said lever F³. It will of course be understood that inasmuch as the grate-sections are independent there will be a separate shoe for each grate-section and also a separate shaker-bar F' and separate lever F³. By referring to Fig. 3 it will be noted that when the shaker-bar F' is pushed rearwardly the shoe F will engage the depending bail and cause the rocker-bar D to be rocked in the direction indicated, and it will of course be understood that the two rocker-bars move in unison and when said bars are rocked one set of grate-bars will be elevated slightly and the alternating set will be dropped or lowered 115 slightly, as most clearly shown, and by working the lever F³ back and forth the entire series of grate-bars can be alternately moved up and down, so as to thoroughly agitate the fuel upon that section of the grate. After the grate-bars have been shaken, as herein shown and described, the parts are returned to their normal positions, as shown in Fig. 2, and, if desired, the other grate-section can have its bars shaken in a similar manner by 120 operating the other lever F³. As previously stated, the cinders, ashes, &c., of one section can be shifted or raked to the other section for the purpose of dumping, and in Fig. 4 I have shown the rear section of grate as being 125 130

dumped, and for the purpose of accomplishing this operation I employ the depending arms E^5 , which are connected to the longitudinal cross-bars E^2 of the cradle E , said depending arms E^5 being preferably arranged adjacent the opposite side of the frame, as most clearly shown in Fig. 15, said arms being connected to a dumping-bar G , which is pivotally connected at its forward end to a lever G' , pivoted to the front of the frame, and it will of course be understood that each cradle is provided with the depending arm and that a separate dumping bar and lever is employed for each section. By reference to Fig. 4 it will be seen that when the dumping-bar is pushed rearwardly the cradle is rocked in the frame and the entire series of grate-bars carried to an inclined position, and owing to the fact that the said grate-bars are interlocked with the rocker-bars all danger of displacement is avoided. As the cradle is rocked the depending bail D^5 is swung rearwardly and upwardly, and the shoe F is caused to move rearwardly a short distance; but when the grate-section is returned to its normal position the depending bail will drop into the recess F^5 of the shoe, and in order to prevent any possible disengagement of these parts I provide the shoe with an upwardly-extending inclined heel-piece F^6 , which serves to guide the depending bail into the recess F^5 . By operating the other lever G' the other section of the grate can be dumped, and it will of course be understood that either section can be dumped when desired or both can be dumped at the same time, if required. It will thus be seen that I provide a simple, durable, and efficient means for agitating or shaking grate-bars of each section and also for dumping the entire section.

The forward ends of the grate-bars are inclined or beveled, as shown at C^6 , and are undercut at their rear ends, as shown at C^7 , so that the adjacent ends of the grate-bars overlap each other, as shown in Fig. 2, and in order to prevent a clear open space at the front and rear of the grate I provide the front of the frame with a series of rearwardly-projecting fingers A^7 , undercut, as shown at A^8 , to overlap the inclined front of the front grate-bars, and the rear side of the frame is formed with forwardly-projecting fingers A^9 , beveled, as shown at A^{10} , and adapted to be overlapped by the rear ends of the rear grate-bars.

The side members of the cradles are protected by means of detachable toothed bars H , which rest upon the said side members of the cradles and are provided with depending wedge-shaped lugs H' , which fit into the entrance to the V-shaped opening E^4 and pre-

vent any longitudinal movement of the said bars H when the cradles are rocked or tilted. The face of the bar H between the teeth is inclined, as shown at H^2 , in order to direct ashes within the frame.

From the foregoing description, taken in connection with the accompanying drawings, it will be seen that I provide the combined shaking and dumping device capable of carrying out all of the objects hereinbefore referred to.

Having thus fully described my invention, what I claim as new, and desire to secure by Letters Patent, is—

1. In a grate, a frame, a cradle journaled in the frame, rocker-bars, carried by the cradle, said rocker-bars having journal portions in alternating planes, webs connecting said portions, the journal portions being provided at their ends with inwardly-extending lugs, and a plurality of grate-bars, said bars resting in the journal portions of the rocker-bars, and engaged by the said lugs.

2. In a furnace-grate, the combination with the grate-bars, having bearing portions provided with laterally-projecting lugs, of the rocker-bars having journal portions provided with inwardly-extending end lugs adapted to engage the lugs of the bars, together with means for rocking the said bars.

3. In a furnace-grate, the combination with a series of grate-bars having bearing portions each provided with laterally-projecting lugs, the bearing portions of adjacent bars being in different horizontal planes, of rocker-bars having journal portions adapted to engage said bearing portions and provided with lugs adapted to coact with the lugs thereof, and means for rocking said rocker-bars.

4. In a furnace-grate the combination with the cradle and means for rocking the same, of the rocker-bars mounted in the cradle, grate-bars arranged thereon, and detachable toothed bars arranged upon the ends of the cradle and adapted to move therewith.

5. In a furnace-grate, a dumping-section comprising a plurality of grate-bars, rocker-bars supporting the grate-bars, cradles supporting the rocker-bars, said cradles having side and connecting end members, the side members having notches therein, and detachable toothed bars resting on the end members of the cradles, and depending lugs carried by said toothed bars and adapted to engage the notches, as and for the purpose set forth.

JOHN FERGUSON.
